US0D1067794S

(12) **United States Design Patent** (10) **Patent No.:** **US D1,067,794 S**
(45) **Date of Patent:** **** Mar. 25, 2025**

(54) **DISPLAY DEVICE FOR TIRE PRESSURE MONITORING SYSTEM**

(71) Applicant: **Zhigang Huang**, Guangdong (CN)

(72) Inventor: **Zhigang Huang**, Guangdong (CN)

(**) Term: **15 Years**

(21) Appl. No.: **29/900,690**

(22) Filed: **Aug. 23, 2023**

(51) **LOC (15) Cl.** **10-04**

(52) **U.S. Cl.**

USPC **D10/86**

(57) **CLAIM**

The ornamental design for a display device for tire pressure monitoring system, as shown and described.

DESCRIPTION

FIG. 1 is a first perspective view of the display device for tire pressure monitoring system thereof;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a exploded view of the display device for tire pressure monitoring system thereof.

The broken lines in the drawings depict portions of the display device for tire pressure monitoring system that form no part of the claimed design.

1 Claim, 9 Drawing Sheets
